UNITED STATES PATENT OFFICE.

RUFUS F. BOOP, OF GLENIRON, PENNSYLVANIA.

ATTACHMENT FOR LIQUID-POLISH-CONTAINING BOTTLES.

1,088,524.

Specification of Letters Patent.

Patented Feb. 24, 1914.

Application filed April 23, 1913. Serial No. 763,091.

To all whom it may concern:

Be it known that I, RUFUS F. BOOP, a citizen of the United States, residing at Gleniron, in the county of Union and State of Pennsylvania, have invented new and useful Improvements in Attachments for Liquid-Polish-Containing Bottles, of which the following is a specification.

The invention relates to an attachment for liquid polish containing bottles, which attachment is designed to be removably secured to the bottle and to provide a construction whereby any desired quantity of fluid from the bottle may be delivered to the brush.

The main object of the present invention is the provision of an attachment formed at one end for removable connection with a bottle or similar receptacle and at the opposite end with a brush, an intermediate valve controlling the flow of liquid through the attachment to the brush, the valve being manually opened by endwise pressure upon the attachment and controlling the quantity of liquid flowing through the attachment in accordance with the extent to which the valve is open.

The invention in its preferred form of details will be described in the following specification, reference being had particularly to the accompanying drawings, in which:—

Figure 1 is a perspective view illustrating the improved attachment and showing the same applied to the bottle. Fig. 2 is a vertical central section through the attachment.

With particular reference to the accompanying drawings, the improved attachment comprises what may be termed a delivery tube 1 having a conical bore 2 extending longitudinally therethrough. At that end of the tube at which the bore is of greatest diameter there is secured to or formed integral with the tube a sleeve connector 3 which, beyond the end of the tube, is internally threaded as at 4, for co-operation with the exterior threads 5 on the neck, 6, of the liquid polish containing bottle 7.

Slidably mounted upon the tube 1 at the

end opposite the connector 3 is what I term 50 a head 8, said head including a truncated conical section 9 to which the bristles of the brush are secured in any appropriate manner, the head also including an annular extension 10 forming a finger grip and by 55 means of which the head is moved. A spring 11 is coiled about the tube intermediate the connector 3 and the head 8 serving to normally maintain the head at its limit of outward movement on the tube. 60

Mounted in the conical bore 2 of the tube 1 is a plug valve 12, said valve being of a size to coöperate with and close the bore 2 at the point about midway the length of the tube. A valve rod 13 is fixedly secured to 65 the plug valve at one end and at its opposite end to a bridge strip 14 extending diametrically of the opening in the head, which communicates with the bore. By this construction the plug valve is fixed with relation to 70 the head, and as said head is longitudinally movable on the tube it is obvious that the head may be moved downwardly on the tube against tension of the spring with the effect to provide a space intermediate the plug 75 valve and the wall of the bore 2, the size of the space increasing the nearer the valve approaches the upper end of the tube.

In operation, it will be apparent that with the attachment secured to the bottle containing polish of any liquid type, any desired quantity of such polish may be delivered to the brush or on to the article being polished by moving the head longitudinally of the tube against tension of the spring, and 85 that upon the release of the upward pressure on the head, the spring will operate to automatically close the valve and cut off the flow. 80

What is claimed is:—

An attachment for polish containing bottles including a tube having an upwardly tapering bore, said tube being formed at one end for removable connection with the bottle neck, a head slidably mounted on the tube, said tube being terminally formed with 95 a lateral projection to limit outward movement of the head, a spring encircling the tube and bearing against the head, an an-

nular extension surrounding the head to provide a finger grip, a valve operative in the tube bore, a rod connecting said valve and slideable head for opening and closing the valve, and bristles secured within the head and projecting beyond the upper end thereof.

In testimony whereof I affix my signature in presence of two witnesses.

RUFUS F. BOOP.
